A. O. Stenwick
BY his ATTORNEY:

A. M. Carlsen.

UNITED STATES PATENT OFFICE.

ALBERT O. STENWICK, OF RED WING, MINNESOTA.

BLOCK OF CLAY OR CONCRETE FOR SEWERS, &c.

1,268,294.

Specification of Letters Patent. Patented June 4, 1918.

Application filed March 15, 1917. Serial No. 155,087.

To all whom it may concern:

Be it known that I, ALBERT O. STENWICK, a citizen of the United States, residing at Red Wing, in the county of Goodhue and State of Minnesota, have invented new and useful Blocks of Clay or Concrete for Sewers, &c., of which the following is a specification.

My invention relates to blocks for the construction of sewers and other structures for which blocks of burned clay or concrete may be used.

The main objects of the invention are, first, to provide extra strong, durable segmental blocks for the construction of large sewers. Second, to firmly unite the ends and edges of such blocks. Third, to so form the blocks that the bottom of the sewer will have several small channels instead of a single large bottom channel which is well-known to cause lodging of sewerage and clogging of the sewer. Fourth, to so construct said sewer blocks that they may be burned without cracking.

In the accompanying drawing, Figure 1 is an end elevation of a large sewer constructed of my improved blocks. Fig. 2 is an enlarged portion of Fig. 1. Fig. 3 is a perspective view of one of the blocks used in the bottom of the sewer. Fig. 4 is a section on the line *a—a* in Fig. 2. Fig. 5 is the middle portion of Fig. 4 modified. Fig. 6 is a perspective view of two of the wedges employed to lend firmness to the joints of the blocks.

Referring to the drawing by reference numerals, it will be observed in Fig. 1 that the inner faces 7 of the blocks 6 in the main upper part of the sewer are plain segmental faces with a curvature corresponding to the radius of the sewer; but the blocks 8 forming the lower part of the sewer have their inward or upward segmental faces formed with longitudinal grooves 9 for more or less water to run along many or few of them and thus move the sewerage along with the force of water running in a channel and not like water having lost its force by being spread thinly upon a broad surface forming the bottom of a sewer.

As best shown in Fig. 2, but also in Fig. 1, the adjacent joined edges or sides of the blocks are each formed with two ribs 10, 11, each of which is formed with a V-shaped groove in which to receive a V-shaped edge

of the adjacent ribs of the other block, said ribs having also adjacent flat faces 12 and 13 with an intervening space between them, and in said space are tightly inserted overlapping wedges 14 and driven home in cement mortar so as to hold the ribs 10, 11, firmly in the grooves and thereby give great rigidity to the sewer against both inward and outward pressure. The wedges 14 are made of the same kind of material as the blocks. To make the V-shaped edges of the ribs more substantial both for handling and for service, they are blunt or trunked as best shown in Fig. 3.

The adjacent ends of the blocks are provided one with a groove having a face 15 parallel to the segmental face of the block and one inclined face 16, the other block having a rib 17 fitting in said groove.

Each block is also formed with longitudinal ducts 18 near its inner face, and larger longitudinal ducts 19 near the outer segmental face and between said small and large ducts is a strong segmental web 20, lightened only by a series of small ducts 21 for the heat to enter into during the burning process, so as to make the material swell uniformly and thus avoid cracking.

In building the sewer suitable cement mortar is applied to all joints to make the structure water-tight. And during the constructing work the ducts 19 may serve as escape ducts for water which will often enter into the trench in which the sewer is being built.

As already partly stated, the interlocking edges of the blocks and the wedges employed to hold the part interlocked are applicable not only to sewer construction but also for building block of artificial stone, concrete and tiles in silos and buildings in general, and especially where the wall, roof, ceiling or floor involved is of arched or curved form.

What I claim is:

1. Building blocks adapted to be fitted together in a structure, said blocks having each an outer and an inner main face and adjoining faces to form joints, said adjoining faces having each a pair of spaced parallel ribs, each with a longitudinal groove near the block, whereby a lateral ridge is formed on each rib, said ridges arranged in opposite directions on the adjoining faces of the blocks so as to engage with the ridges of,

one block in the grooves of the ribs on the other block, and when so engaged to form an angular space between the ungrooved sides of the two ribs about midway between the inner and outer main face of each block, and a series of overlapping double-edged wedges adapted to be driven into said space so as to hold the ribs with the ridges firmly engaged in the grooves.

10 2. Building blocks adapted to be fitted together in a structure, said blocks having each an outer and an inner main face and adjoining faces to form joints, said adjoining faces having each a pair of spaced parallel ribs, each with a longitudinal groove near the block, whereby a lateral ridge is formed on each rib, said ridges arranged in opposite directions on the adjoining faces of the blocks so as to engage with the ridges 15 of one block in the grooves of the ribs on the other block, and when so engaged to form an angular space between the ungrooved sides of the two ribs about midway between the inner and outer main face 20 of each block, and a series of overlapping double-edged wedges adapted to be driven into said space so as to hold the ribs with the ridges firmly engaged in the grooves, 25 said grooves and ridges fitting therein having

ing inclined adjacent faces whereby to draw 30 the blocks together.

3. Building blocks adapted to be fitted together in a structure, said blocks having each an outer and an inner main face and adjoining faces to form joints, said adjoining faces having each a pair of spaced parallel ribs, each with a longitudinal groove near the block, whereby a lateral ridge is formed on each rib said ridges arranged in opposite directions on the adjoining faces of the blocks so as to engage with the ridges of one block in the grooves of the ribs on the other block, and when so engaged, to form an angular space between the ungrooved sides of the two ribs about midway between the inner and outer main face of each block, and a series of overlapping double-edged wedges adapted to be driven into said space so as to hold the ribs with the ridges firmly engaged in the grooves, said grooves and ridges fitting therein having inclined adjacent faces whereby to draw the blocks together, said blocks being curved so as to form when put together an arched or even cylindrical structure.

In testimony whereof I affix my signature.

ALBERT O. STENWICK.
